United States Patent Office.

LUTHER BOARDMAN AND NORMAN S. BOARDMAN, OF EAST HADDAM,
CONNECTICUT.

Design No. 2,794, dated October 1, 1867.

DESIGN FOR A SPOON-HANDLE.

The Schedule referred to in these Letters Patent and making part of the same.

TO ALL WHOM IT MAY CONCERN:

Be it known that we, LUTHER BOARDMAN and NORMAN S. BOARDMAN, of East Haddam, in the county of Middlesex, and State of Connecticut, have invented a new and improved Design for Spoon and Fork-Handles; and we do hereby declare that the following is a full, clear, and exact description thereof, which will enable others skilled in the art to understand the same, reference being had to the accompanying drawings, forming part of this specification.

Figure 1 represents a front view of a spoon-handle ornamented with our new design.

Figure 2 is a back view of the same.

Similar letters of reference indicate corresponding parts.

This design relates to a new style of ornamenting for the upper part of a fork or spoon-handle, whereby the appearance of the same is greatly improved.

The invention consists in suspending a medallion or other suitable ornament, by means of tasselled cords, from a hook which is formed in arabesques arranged around the edge of the handle. On the back of the handle the tasselled cord is also arranged, being suspended from a hook formed by beaded mouldings arranged around the rim of the handle.

A represents the spoon or fork-handle. Around its edge is arranged, in front, a beaded moulding, *a*, ornamented by foliage or arabesques *b*, as shown in fig. 1. The beaded moulding does not extend around the upper edge of the handle, but near the same it is turned in from each side, and the two mouldings from the two edges of the spoon are joined, forming a hook, *e*, at their junction, as shown in fig. 1. From this hook is suspended, by means of a cord or cords, *d*, an ornamental medallion, *e*, or any other suitable design, as, for example, a fruit-basket. The ends of the cord are provided with tassels *f*, as shown. On the back of the handle A a hook, *c'*, is formed, by beaded mouldings *a'*, in a similar manner as on the front of the handle. The beaded mouldings are plain on the back, that is, without arabesques. A tasselled cord, *d'*, is suspended from the hook *c'*, as is clearly shown in fig. 2.

We claim as new, and desire to secure by Letters Patent—

The design for a spoon-handle, substantially as shown and described.

LUTHER BOARDMAN,
NORMAN S. BOARDMAN.
